Paul de Miles, Inventor
By his Attorney
Charles E. Heydt

UNITED STATES PATENT OFFICE.

PAUL DE MILES, OF NEW YORK, N. Y.

ELECTRIC FURNACE.

1,317,864.

Specification of Letters Patent.

Patented Oct. 7, 1919.

Application filed January 25, 1918. Serial No. 213,653.

To all whom it may concern:

Be it known that I, PAUL DE MILES, a subject of the King of Belgium, residing at borough of Manhattan, city, county, and State of New York, have invented certain new and useful Improvements in Electric Furnaces, of which the following is a specification.

This invention relates to electric furnaces.

10 More particularly, the invention is directed to electric furnaces of the oven type heated by electrical resistance material.

In the preferred forms of the invention, the electrodes are made hollow to provide 15 for cooling jackets for the flow of a suitable cooling medium. Also, means are provided for holding the electrodes under pressure in good electrical contact with the electrical resistance material.

20 When desired, the oven is supported on the casing of a transformer, utilized to transform any supplied current to the desired voltage and amperage suitable for the furnace.

25 Other features and objects of the invention will be more fully understood from the following description and the accompanying drawings, in which—

Figure 1 is a perspective view of an embodiment of my invention, showing the oven furnace mounted on the transformer casing; and

Fig. 2 is a detail central sectional view through an electrode.

35 The embodiment of the invention illustrated in the figures is of the oven type. However, the invention is applicable to all other types of inclosed furnaces.

The oven 1 comprises the outer casing or 40 shell 2, lined on its walls with brick 3, of suitable resistant properties.

The oven 1 also comprises the cover 4, adapted to be sealed with the oven walls 3 by means of the clamps 5. The oven is also 45 provided with the closure or door 6. The bottom or other supporting portion of the interior of the oven is adapted to receive or support a crucible or like container for the metal or other material to be heated or 50 melted.

The heating element of the furnace comprises the electrical resistance rod 7 of carbon, or the like, the same being located within the oven to provide the desired heat.

55 The number of resistance heating elements

is determined by the effective cross-section of the same and the temperature desired.

The electrodes 8, 9 of cast iron or the like are arranged in good electrical contact with the resistance element or elements. Preferably, such arrangement is effected by the provision of means to maintain good electrical contact at all times of operation. One such means is indicated in the embodiment illustrated, comprising the abutments 10, 11, 60 held under pressure against the respective electrodes 8, 9 by the adjustable cross-rod 12, as by means of the lock-nuts 13, threaded to said cross-rod 12. The opposite ends of the abutments 10, 11 are secured to the brackets 14 fixed to but electrically insulated from the side walls of the oven. As shown, the electrodes project through the respective side walls and sealed with magnesite, and the cross-rod behind and outside of the rear 70 walls of the oven. Electrical insulation of the rod 12 is attained by the insulating ring or washer 15, or equivalent.

To further insure the desired pressure, the clamping screws 16 are provided, threaded 80 in the respective abutments and engaging the respective electrodes.

The electrodes 8, 9 are preferably hollow to provide cooling jackets, having the inlets 17 respectively connected to the rubber in-flow piping 18 and also having the outlets 19 respectively connected to the rubber out-flow piping 20. The pipe 21 represents a suitable supply pipe of cooling medium such as water. As shown, the cooling means is 90 preferably disposed exterior of the walls of the furnace.

If desired, the oven or furnace is supported on the casing 22 of a transformer or the like. The regulating arm of the resistance or impedance is indicated at 23. The electrical cables 24, 25, are respectively connected to the electrodes 8, 9.

Whereas I have described my invention by reference to specific forms thereof, it will 100 be understood that many changes and modifications may be made without departing from the spirit of the invention, as defined by the appended claims.

I claim:

1. An electrical furnace comprising a hollow casing provided with openings, an electrical resistance rod positioned in said openings extending through the interior of said casing, electric terminals adapted to engage 110

105

said resistance rod at spaced locations thereof, means for exerting pressure on said terminals to thereby more firmly engage said resistance rod, said pressure exerting means comprising parts respectively engaging said electrodes and means for electrically insulating said pressure exerting means from said electrodes.

2. An electrical furnace comprising a hollow casing provided with openings, walls of heat resistant material, an electrical resistance rod positioned in said openings and extending interiorly of said casing between said walls, terminals adapted to engage the respective ends of said resistance rod, means for exerting pressure on said terminals to thereby more firmly engage the ends of said resistance rod, said pressure exerting means comprising individually movable parts respectively engaging said electrodes and means for electrically insulating said pressure exerting means from said electrodes.

3. An electrical furnace comprising a hollow casing provided with openings, walls of heat resistant material, an electrical resistance rod positioned in said openings and extending interiorly of said casing between said walls, terminals adapted to engage the respective ends of said resistance rod, means for exerting pressure on said terminals to thereby more firmly engage the ends of said resistance rods, said pressure exerting means comprising individually movable parts respectively engaging said electrodes, means for electrically insulating said pressure exerting means from said electrodes, hollow members respectively adjacent said electrodes and passages connecting said hollow members individually and adapted to convey a cooling fluid.

In testimony whereof I have signed this specification this 22nd day of January, 1918.

PAUL DE MILES.
